ROTARY RAZOR SHEAR HEAD

Robert Richard, Morges, Switzerland, assignor to
 Richard & Ammann S. A., St. Jean, Morges,
 Switzerland

Application December 29, 1948, Serial No. 67,956

2 Claims. (Cl. 30—43)

1

This invention relates to cutting heads for electric razors, of the type in which a pair of blades rotate about an axis with respect to which their cutting edges are approximately radial, the blades travelling over the inner surface of a thin metal grid or grating, the outer surface of which is held against the skin so that hairs thereon project through the openings in the grid or grating and are severed by the rotating blades.

The object of the present invention is to provide a simple blade assembly for a cutting head. The blades have curved cutting edges and are mounted each on one arm of a supporting spring, the two arms comprising approximate half-helices of opposite hand each extending out from a central disc in a counterclockwise direction to a blade receiving portion to which the blade is secured. Each of the blades preferably makes an angle of not more than 45° with a plane perpendicular to the axis of rotation of the blade assembly.

The invention is hereinafter described with reference to the accompanying drawings, in which:

Figure 1 is a sectional elevation of a removable cutting head for an electric rotary razor according to the invention;

Figure 2 is an end view of the cutting head shown in Figure 1, the grid or grating being omitted from one half of the view;

Figure 3 is a diagram showing the blade assembly on a larger scale; and

Figures 4 and 5 are diagrams showing two methods of securing the blades to the supporting spring.

While the drawings show a cutting head which is detachable from the body of the razor which contains the electric motor for driving the blades, it is to be understood that the invention is applicable also to razors in which the cutting head is permanently attached to the body. In such a case the supporting spring may be mounted directly on the spindle of the electric motor.

Referring to the drawings the cutting head comprises a cap 1, the outer end of which is closed by a domed sheet 2 of very thin bronze (a suitable thickness being 0.05 mm.), which sheet is perforated with a large number of small holes to form a grid or grating. The sheet 2 is kept in position and held in tension by a collar 3 fitting within the cap 1. Bayonet slots 4 are provided for securing the cap to a razor body.

A spindle 5 carrying a coupling unit 6 for engagement with a complementary coupling unit in the body is mounted in a bearing 7 in the

cap, a lubricating bushing 8 being provided in the bearing. The bearing is supported in a spider 9 secured in the cap by a spring ring 10, which enables the spindle to be easily removed for inspection and maintenance.

The spindle 5 has secured to it by screw threads a support 11 to which is secured a spring member 12 formed from a flat resilient plate, the member having two tapering arms 13 and 14 which form approximately half-helices of opposite hand to one another. To the outer end of each arm is welded a cutting blade 15 or 16, the blades being of a thickness of a fraction of a millimeter, and having, in plan view, the shape of a scimitar. The blades are mounted so as to lie in planes making angles of between 20° and 45° with a plane perpendicular to the axis of rotation of the blades, the angle depending on the thickness of hair which the razor is intended to cut.

The curvature of the cutting blades 15 and 16 along their cutting edges is tangential to the domed part of the grid 2, so that during rotation, the blades, due to centrifugal force, are pressed against the inside surface of the grid, and they therefore produce a certain braking effect which tends to fix a maximum speed of rotation of the blades.

Figures 4 and 5 show two alternative arrangements of the connections between the spring arms 13 and 14, and the blades 15 and 16. In Figure 4, the blade 15 is welded to a bent-over end portion of the arm 13 and thus makes an angle with the said arm, whereas in Figure 5 the blade 16 is welded to the arm 14 itself, and lies parallel to the said arm.

The spring arms 13 and 14 act to some extent as fan blades and produce a flow of air which assists in cooling the grid 2, to compensate for the heating tendency due to the friction of the blades 15 and 16 thereon.

I claim:

1. A rotary shear head for dry shavers, comprising, a casing having means at its lower end for detachably connecting with the bottom of the razor which constitutes a handle and houses a driving motor, the upper end of said casing having an annular off-set flange surrounding an opening, said casing also having a groove on the intermediate portion of its inner face, a perforated grid element of spherical dished formation having its marginal edge portion fitted behind said flange, an annular collar in the casing and having means for clamping the grid to said flange, a spider plate having an outer portion

backing up the collar and having an inner portion constituting a bearing support, a split spring ring normally seated in the groove to hold the spider, collar and grid assembled within the casting, a bearing fitted in the inner portion of the shaft, a bearing fitted in the bearing, a motor spider, a shaft mounted in the bearing, a motor coupling at the lower end of the shaft, a blade coupling at the lower end of the shaft, a blade shaft, a pair of shear blades with arcuate cutting edge disposed in opposite directions and bearing against the inner face of the grid, and helically spaced spring arms having the shear blades mounted on their upper ends and having their lower ends secured to the blade support.

2. In a rotary shear head for dry shavers, the combination, including, a spherical dished perforated grid forming the outer face of the head, a motor driven rotary support in the head and spaced from the grid, and a unitary resilient cutting unit confined between the grid and the support, said unit including a plate mounted on the

support and having helicoidal spring arms integrally connected at their base with diametrically opposite portions of the plate, said arms extending upwardly toward the grid and providing free diametrically opposite terminal portions spaced approximately 90° from the junction of the base of said arms with the plate, and cutting blades secured to the said terminal portions of the arms and having arcuate leading cutting edges wiping the inner face of the grid.
